UNITED STATES PATENT OFFICE.

ALBERT ANDERSON, OF GLENWOOD, MINNESOTA.

POWER-PROPELLED SLED.

1,069,514.

Specification of Letters Patent. Patented Aug. 5, 1913.

Application filed February 15, 1912. Serial No. 677,773.

To all whom it may concern:

Be it known that I, ALBERT ANDERSON, a citizen of the United States, residing at Glenwood, in the county of Pope and State of Minnesota, have invented certain new and useful Improvements in Power-Propelled Sleds; and I do hereby declare the following to be a full, clear, and exact description of the invention, such as will enable others skilled in the art to which it appertains to make and use the same.

My invention has for its object to provide an improved power propelled sled, and to this end it consists of the novel devices and combinations of devices hereinafter described and defined in the claims.

The invention is illustrated in the accompanying drawings, wherein like characters indicate like parts throughout the several views.

Referring to the drawings, Figure 1 is a side elevation of the improved power propelled sled with some parts broken away and with some of the exposed parts shown in section; Fig. 2 is a view, on an enlarged scale, in transverse vertical section taken on the line $x^2 x^2$ of Fig. 1; and Fig. 3 is a detail view in plan showing the intermediate portion of the parts illustrated in Fig. 2.

The numerals 1 and 2 indicate, respectively and as entireties, the body of an automobile and an explosive engine. Front and rear bobs 3 and 4, respectively, support a supplemental skeleton frame 5 on which the body 1 rests. A front bearing bracket 6 and a pair of rear bearing brackets 7 depend from and are rigidly secured to the under side of the supplemental frame 5. The front bracket 6 is located intermediate between the side portions of the supplemental frame 5, and the front bob 3 is pivotally attached thereto at 8. In actual practice, suitable steering mechanism for steering the front bob 3 will be provided, but for the purpose of this case, it is not thought necessary to illustrate the same.

The runners of the rear bob 4 are comparatively short and upwardly extended bearing brackets 9 are rigidly secured to the rear ends thereof. The two bearing brackets 7 are secured on opposite sides of the supplemental frame 5. A transversely and horizontally extended shaft 10 is supported in the lower end portions of the brackets 7. The bearing brackets 9 are loosely journaled on the outer ends of the shaft 10

and connect the runners of the rear bob 4 to the supplemental frame 5 with freedom for oscillatory movements in vertical planes.

Bearings 11 are rigidly secured one to the front end portion of each runner of the rear bob 4 and are axially alined with longitudinally extended bearings 12 formed in the bearing brackets 9. Propeller shafts 13 and 13^a are attached to the runners of the rear bob 4. These propeller shafts extend rearward from the bob 4 and have their forward ends journaled in the bearings 11 and 12. Vertically movable and depending bearing rods 14 have their upper ends slidably mounted in the supplemental frame 5. The rear ends of the propeller shafts 13 and 13^a are loosely journaled in the lower ends of the bearing rods 14. Coiled springs 15 are compressed between the supplemental frame 5 and fixed collars 16 on the bearing rods 14 and yieldingly press the rear ends of the propeller shafts 13 and 13^a downward. Ground engaging spiral propelling blades 17 are axially secured to the propeller shaft 13 and 13^a between the bearings 12 and 14.

The driving shaft 18 of the engine 2 extends horizontally rearward from the engine and is journaled in a pair of laterally spaced and transversely extended bearing braces 19 rigidly secured to the side members of the supplemental frame 5. Keyed to the shaft 18 is a spur gear 20 that meshes with a spur gear 21 keyed to a counter shaft 22 journaled in the bearing braces 19. A sprocket chain 23 runs over a pair of alined sprocket wheels 24 keyed one to the shaft 18 and the other to the propeller shaft 13. And a sprocket chain 25 runs over a pair of alined sprockets 26 keyed one to the counter shaft 22 and the other to the propeller shaft 13^a.

To drive the vehicle forward, the engine is run in a direction to drive the propeller shafts 13 and 13^a in the direction of the arrows marked on Fig. 2.

The propeller shafts 13 and 13^a, together with their propeller blades 17, are interchangeable and they may be substituted one for the other in case it is found desirable to drive the propeller blades in a reverse direction from that shown in the drawings.

Suitable means may also be provided for raising and lowering the rear ends of the propeller shafts from the front seat of the vehicle.

What I claim is:—

1. The combination with a vehicle body, a power propelled rear sled connected thereto with freedom for vertical oscillatory movement, and a front sled connected thereto for steering movement, of a pair of spiral road engaging propeller blades having driving shafts rotatively mounted in fixed bearings on the runners of said rear sled, and means for rotating said shafts, substantially as described.

2. The combination with a vehicle body, a power propelled rear sled connected thereto with freedom for vertical oscillatory movement, and a front sled connected thereto for steering movement, of a pair of hori-

zontally extended driving shafts having their forward ends mounted in fixed bearings on the runners of said rear sled, spiral propeller blades secured to the rear ends of said shafts, bearings on said body for the rear ends of said shafts, and yielding means for holding said propeller blades in engagement with the road with freedom for vertical oscillatory movement with said rear sled, substantially as described.

In testimony whereof I affix my signature in presence of two witnesses.

ALBERT ANDERSON.

Witnesses:

GUSTAV NELSON,
CARL N. NELSON.
